UNITED STATES PATENT OFFICE

128,470

DESIGN FOR A TEXTILE FABRIC

John H. Abt, New York, N. Y.

Application June 19, 1941, Serial No. 101,566

Term of patent 3½ years

To whom it may concern:

Be it known that I, John H. Abt, a citizen of no country and has declared his intention of becoming a citizen of the United States of America, that he is a resident of the city of New York, in the county of New York and State of New York, have invented a new, original, and ornamental Design for a Textile Fabric, of which the following is a specification, reference being had to the accompanying drawing, forming part thereof, wherein the figure of the drawing is a plan view of a textile fabric, showing my new design.

I claim:

The ornamental design for a textile fabric, substantially as shown.

JOHN H. ABT.
